UNITED STATES PATENT OFFICE.

FREDERICK BURGDORF, OF ELYRIA, OHIO.

SLICING OR GRATING MACHINE.

Application filed June 21, 1920. Serial No. 390,399.

To all whom it may concern:

Be it known that I, FREDERICK BURGDORF, a citizen of the United States, residing at Elyria, in the county of Lorain and State 5 of Ohio, have invented certain new and useful Improvements in Slicing or Grating Machines, of which the following is a full, clear, concise, and exact description, such as will enable others skilled in the art to 10 which it appertains to make and use the same.

My invention relates to slicing or grating machines; more particularly it relates to that type of machine of the above character 15 used mainly for slicing or grating vegetables.

Among the objects of my invention are the following:

To provide a slicing or grating machine 20 of the rotary type of special construction; to provide a slicing drum of special construction; to provide a frame for operating a slicing drum or a grating drum; to provide a frame of the above character for driving 25 a slicing or a grating drum, and in combination with said drums, of mechanical means for removing the sliced or grated material; and to provide other details of construction tending to increase the efficiency 30 and serviceability of a slicing or grating machine.

To accomplish the foregoing and other useful ends, my invention comprises means hereinafter more particularly set forth and 35 claimed.

Referring to the drawings, Figure 1 is a side elevation of the machine showing the slicing drum in position. Figure 2 shows the grating drum and Figure 3 shows the 40 device for removing the sliced or grated material.

In Figure 1, the main frame 2 of the machine is shown as consisting of a standard provided with a suitable clamp bracket 45 formed integral at the lower end having a clamp screw extending through the lower portion thereof so that the machine may be securely fastened in any suitable locality when it is desired to operate the same. On 50 the upper end of the frame is provided an integral hopper 3, provided with a lid 4, integral with which there is formed a cylindrical collar 5 projecting into the hopper. Near the central portion of the frame there 55 is a bearing 6 through which a shaft 7 passes. This shaft is held in position be-

tween the collars 8 and 9. On the left of the shaft there is provided a suitable crank 10; immediately to the right of the collar 8 and integral therewith, there is provided 60 a spider 11, having on its periphery a pin 12. The slicing drum 13 is provided with a slot which engages the pin 12 whereby the drum 13 may be slipped on the spider 11 and prevented from rotating by the pin 12 and 65 at the same time hold in position. In my arrangement, I provide an auxiliary spider 14, having a collar arrangement 15, which receives the front end of the drum 13. It will be seen that the threaded end of the 70 shaft 7 extends through the hub 16 of the spider 14 and that the nut 17 may be screwed on the end of the shaft 7, to hold the spider in position.

In setting up the machine, it will be understood that the rake device 18 shown in Figure 2 is slipped into position inside of the drum and over the shaft 7 before the spider 14 is put in place, as indicated in Figure 1. Whenever the operator desires to withdraw 75 any of the material that has accumulated within the cylinder, he merely pulls the right-hand terminal of the hub 19 and draws the rake to the right, which, of course, has the effect of removing any material that may 80 have accumulated inside.

I have shown in Figure 2 the grating drum. This can be substituted for the slicing drum shown in Figure 1, in which case 85 the machine may be used as a grater.

I wish it to be understood that although I have shown the cutting drum and the grating drum, plane cylinders, they may be conical in shape. In such case, the narrow head may be arranged to engage the spider 90 11 and the larger head may be engaged by the spider 15, or vice versa. In either case 95 the spiders will have to be made of different sizes. The spider that is to engage the smaller head will have to be of smaller diameter than the spider that is to engage the larger head. Under certain conditions it would be preferable to have the smaller head of the conical cylinder toward the rear and the larger toward the front. With this arrangement the material would be automatically ejected from the machine and in that case the rake 19 will be unnecessary.

I claim the following as my invention:

1. In a slicing machine, a frame standard, 110 a rotatable drum mounted to said frame, a hopper located over a cutting drum and an

auxiliary hopper within said first hopper, and pivoted on said first hopper.

2. In a vegetable slicing machine, a cutting drum on a rotatable shaft, a shuttle rake slidably mounted on the shaft in said drum whereby it may be operated by hand to remove the cut vegetable from the bottom side of the drum, a crank on one end of

the shaft, a thread on the other end of the shaft, a spider mounted on said shaft for supporting said drum, and a thumb screw on said shaft for screwing said spider in position.

In witness whereof, I have hereunto signed my name this 18th day of June, 1920.

FREDERICK BURGDORF.
